UNITED STATES PATENT OFFICE

146,007

DESIGN FOR A FIGURE TOY

Joseph S. Looney, Beaumont, Tex.

Application October 5, 1945, Serial No. 122,539

Term of patent 14 years

(CL. D34—15)

To all whom it may concern:

Be it known that I, Joseph S. Looney, a citizen of the United States, residing at Beaumont, in the county of Jefferson and State of Texas, have invented a new, original, and ornamental Design for a Figure Toy, of which the following is a specification, reference being had to the accompanying drawing, forming part thereof.

I claim:

The ornamental design for a figure toy, substantially as shown.

JOSEPH S. LOONEY.
